Primary Examiner — Kelley A Donnelly*(74) Attorney, Agent, or Firm* — Medley, Behrens and Lewis, LLC; Lorri W. Cooper(57) **CLAIM**

The ornamental design for a basket, as shown and described.

DESCRIPTION

FIG. 1 is a perspective view of an example basket; FIG. 2 is a front plan view thereof; FIG. 3 is a rear plan view thereof; FIG. 4 is a right side plan view thereof, with the left side plan view being a mirror image thereof; FIG. 5 is a top plan view thereof; and, FIG. 6 is a bottom plan view thereof. The broken line showings of FIGS. 1-6 are for illustrative purposes only and form no part of the claimed design.

1 Claim, 4 Drawing Sheets(56)
